UNITED STATES PATENT OFFICE.

MARTIN KÜHNE, OF PORTLAND, OREGON

HOLLOW CONCRETE FLOOR CONSTRUCTION.

1,118,456.

Specification of Letters Patent.

Patented Dec. 1, 1914.

Application filed October 4, 1913. Serial No. 783,474.

To all whom it may concern:

Be it known that I, MARTIN KÜHNE, a citizen of the United States, and a resident of the city of Portland, county of Multnomah, State of Oregon, have invented a new and useful Improvement in Hollow Concrete Floor Construction, of which the following is a specification.

My invention relates to the modern construction of concrete floors, referring in particular to that construction which involves the forming of hollow or air spaces in the concrete floor slabs; and my invention has for its object the providing of forms, or centers, which combine maximal efficiency with minimal cost of manufacturing and putting in place.

A further object of my invention is to provide means for joining the adjacent forms in a practical and efficient manner; also, to suspend the metal ceiling lath in a secure manner by means not dependable on the keys formed by the concrete in the openings of the metal lath.

Another object of my invention is to make my forms with as few stiffening ribs or elements as possible, but so form these elements as to safely carry all the load that may be imposed on the form; also, to avoid any sagging in the field or web at the top of a form, and thus prevent the undesirable consequences due to such defect.

The several features of my invention are more readily understood by describing in the first instance the accompanying drawings, in which:

Figure 1 is a longitudinal section of a concrete floor slab embodying my invention; Fig. 2 is a top view of the forms used in the construction of such floor slab, also showing the bridges connecting adjacent forms, and the metal ceiling lath as independently suspended from such bridges and the reinforcing bars supported by the latter; Fig. 3 is a perspective detail of one of the bridges connecting adjacent forms; Fig. 4 is a perspective view showing a section of a floor slab, with part of the concrete removed so as to show all of the metal reinforcing parts entering into such construction; Fig. 5 is a top view similar to Fig. 2, except that the form is of different construction than shown in Fig. 2; the particular form here shown being four-sided and embodying other details which will be fully described in the body of the specification; Fig. 6 is a vertical section

taken along the right-angular line A—A of Fig. 5; this figure also showing some of the concrete mass; and Fig. 7 is a detail of construction hereinafter fully explained.

Referring in the first instance to the illustration of my invention in Figs. 1 to 4 inclusive: *b* represents the metal ceiling lath, and *d* the bridges connecting adjacent forms *i*. The type of form here shown comprises a sheet metal structure having sides and an arched top. The latter is made with pressed-out ribs or primary stiffening elements *j*, protruding outwardly from the body of the form, as more clearly seen in Fig. 1. The primary ribs *j* are bent outwardly, as mentioned, so as to impart maximum inherent resisting power to the metal form with respect to the weight of the concrete mass poured over the form. In the flat fields or webs between the primary ribs *j* are formed a plurality of transversely disposed supplemental ribs or stiffening elements *k*, also pressed outwardly, as more clearly shown in Figs. 1 and 4. Said supplemental ribs have a transverse enlargement maximal midway between the adjacent primary ribs, so as to have their greater sustaining power at that point, and adapt them to safely take care of any stress which the field or web between the primary ribs may have to sustain. My reason for the described particular construction of said supplemental ribs is this: Midway between the primary ribs there is greater stress imposed by the weight of the concrete mass than close to such ribs. Hence unless efficient means are provided for taking care of this stress there would be a tendency for said intermediate field or web to sag at said midway point, which sagging would tend to aggravate the circumstances; for it would form a pocket in which an abnormal quantity of material is reposed, thus imposing further weight upon the sagging field, and, besides, causing a waste of the concrete filling the pockets formed by such sagged places, and in so doing unnecessarily increasing the cost of the building.

The bridges *d* are formed of sheet metal and have their ends *e* made V-shaped, or of channel form, so as to receive the sides *i'* of the forms, as shown in Figs. 1 and 4. The bridges *d* rest on the metal ceiling lath *b*. To prevent them from sagging, due to the weight of the concrete mass poured on them, I provide each bridge with a leg *g*. This leg is preferably pressed out of the

body of the bridge, is arranged perpendicularly to the body, and serves as a stiffening means for the body, besides supporting it. The leg *g* is disposed diagonally to the axis of the bridge-body, so as to insure that the leg *g* will straddle the cut-out spaces *b'* of the metal ceiling lath under all conditions, and thus serve as a dependable support for the center of the bridge.

- 10 Reinforcing bars *f* are placed on the bridges, as shown, and the metal ceiling lath is wired to said reinforcing bars, as shown at *h*, and may also be wired to the bridge, as shown at *h'* in Fig. 2. My purpose in so 15 securing the metal lath is this: In case of fire, the cement keys might be insufficient to hold the ceiling lath in place, while by having the ceiling lath fastened to the reinforcing bars they are supported independently of the concrete mass and render the 20 floor much more durable even in a severe fire.

The primary ribs *j* extend with the arc and slope upwardly to the apex *j'*, so as to 25 give maximum strength to my form.

In the other type of my forms or centers, illustrated in Figs. 5 and 6, the features not changed are designated by the same letters as designate like parts in the preceding figures. As mentioned, this type of my form has four sides, and is designed to be used where the adjacent forms are to be supported at, and connected together on four sides. In this form of construction the top 35 *m* is provided with radial hips or primary stiffening elements *q*. The top is further arched so as to come to the apex *r*, thus producing the same effect here as at *j'* in the other types of my form. In the flat fields 40 between the hips or primary stiffening elements *q* are pressed out supplemental ribs or stiffening elements *n*, made with a trans-

verse enlargement toward that point of the field where the primary stiffening elements are widest apart. In order to make these 45 forms of great strength, I prefer also to make the sides with pressed-out vertical ribs, as at *o*.

I claim:

1. A floor-form made of non-corrugated 50 sheet metal, having primary, deep stiffening-ribs pressed out, and supplemental, deep stiffening-ribs pressed out between the primary stiffening ribs; said supplemental stiffening ribs being arched in varying cross section 55 with the greater span midway between the primary stiffening ribs and tapering at the end toward the latter.

2. A floor-form made of non-corrugated sheet metal, having primary, deep stiffening-ribs pressed out and extended parallel to each other in one direction, and supplemental, deep stiffening-ribs pressed out between the primary stiffening ribs; said supplemental stiffening ribs being arched in varying cross 60 section with the greater span midway between the primary stiffening ribs and tapering at the end toward the latter.

3. A floor-form made of non-corrugated sheet metal, having primary, deep stiffening-ribs pressed out and extended parallel to each other in one direction, and supplemental, deep stiffening-ribs pressed out between and perpendicular to the primary stiffening ribs; said supplemental stiffening 70 ribs being arched in varying cross section with the greater span midway between the primary stiffening ribs and tapering at the ends toward the latter.

MARTIN KÜHNE.
